UNITED STATES PATENT OFFICE.

ARTHUR W. CAPS, OF TOPEKA, KANSAS, ASSIGNOR TO THE PIERSEN MANUFACTURING COMPANY, OF TOPEKA, KANSAS, A CORPORATION OF KANSAS.

ENGINE-CYLINDER-COOLING MEANS.

1,417,028.

Specification of Letters Patent. Patented May 23, 1922.

Application filed October 22, 1920. Serial No. 418,846.

To all whom it may concern:

Be it known that I, ARTHUR W. CAPS, a citizen of the United States, residing at Topeka, in the county of Shawnee and State 5 of Kansas, have invented certain new and useful Improvements in Engine-Cylinder-Cooling Means; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to a system for cooling engine cylinders and is particularly applicable for use in connection with stationary engines where the temperature reducing effect on the water or other cooling liquid is entirely dependent upon an impeller for subjecting the water from the cooling jacket to the action of air to reduce its temperature.

20 In stationary engine practice it is somewhat difficult to keep the water in the circulating system cool enough to properly function because all of it must be passed through or adjacent to some heat absorbing medium. This is not true of portable engine practice, that is, where the engine is placed upon a fast moving vehicle, because travel of the fast moving vehicle creates a 25 circulation of air which carries off considerable heat from the engine, the tubes of the water circulating system, etc.

With a stationary engine, then, it becomes necessary to provide a more efficient means of dissipating the heat in the water 30 passing from the water jacket, so as to render it capable of again absorbing the heat from the combustion cylinder of the engine, when it re-enters the water jacket.

My invention contemplates the provision 35 of means for insuring a proper lowering of the temperature of the water as it issues from the cooling jacket so that it may be again available for use as a cooling medium.

I have also provided means whereby the 40 supply of water may be automatically augmented from time to time and to this end I have provided a reservoir from which the water may be induced to flow through the water jacket, the reservoir being provided 45 with an automatically operating valve

which will become effective when the level therein drops below a determined point to admit additional water, the added amount being only equal to that dissipated by evaporation losses during the operation of the 60 cooling system. Therefore, while a proper amount of water within the reservoir will be maintained at all times, the system will not be wasteful, because only such added amounts may enter the reservoir as will take 65 care of the losses as above described and, therefore, it will be apparent that the system will be quite economical in so far as the consumption of cooling water is concerned, this being a material advantage in 70 localities where there is a scarcity of water.

The general organization of my invention consists broadly in providing a closed circulating system in which there is some means for inducing a flow of water from 75 a normally closed reservoir to a cooling jacket, directing the heated water from the cooling jacket to an impeller, which fractionates the discharged water in order to bring it into contact with the forced circulation of air, the air being adapted to absorb the excess heat from the water and allow the water to pass back into the reservoir to be used over again.

I have also provided a cooling tower or 80 condenser in connection with the impeller or fractionator which may have a tendency to condense the steam or vapor if any, but this may be dispensed with if desired.

In the drawings.

Fig. 1 is an edge elevational view of an engine constructed in accordance with my invention, the circulating system being shown partly in section.

Fig. 2 is a side elevational view of an 95 engine equipped with a circulating system, and

Fig. 3 is a similar view of the side opposite to that illustrated by Fig. 2, showing the air intake for the impeller casing.

Referring now to the drawings by numerals of reference:

1 designates a conventional form of explosion motor illustrated as supported upon a base 2, which is hollow to provide a reservoir 3 to contain a supply of water to be used in the circulatory system for cooling the cylinder 4. Within the reservoir 3 is a circulating pump 5 which will cause a circulation of water from the reservoir 3 105 110

through the tubular connection or pipe 6 into the water jacket 7, which surrounds the cylinder 4. The inlet for the water jacket is at the bottom, as indicated at 8, while 5 its outlet 9 is at the top, the port 9 discharging into a container 10 having a discharge port 11 which discharges into an annular chamber 12 of a hub 13 of an impeller 14 on the crank shaft 15 of the engine. The hollow hub 13 is provided with a plurality of openings 16 in its outer wall which, when the impeller is rotating, will 10 fractionate the water issuing into the chamber 12 so that the subdivisions of the stream 15 from the discharge or nozzle 11 will be thrown by centrifugal force outwardly between the air vanes 17, where they will mix with air before being passed through the slotted rim 18 provided with the blades 19 15 in the perimeter thereof, for the purpose of directing the mixed water and air radially 20 through the impeller.

By reference to Fig. 1 it will be observed that the water can only enter the hollow hub 25 13 through an annular opening 20 on one side of the impeller, while air enters the impeller from the opposite side, being directed through an enlarged opening 21 in the impeller casing 22 which surrounds the 30 impeller and which communicates with the reservoir 3. Therefore, after the air and water have intimately mixed so that the air will have an opportunity to absorb the excess heat in the cooling water, the air is 35 permitted to pass to atmosphere while the water is re-directed back into the reservoir to be again passed through the tube 6 and through the water jacket to function as a heat absorbent.

40 I also provide a condensing tower 23 at the top of the casing 22, the condensing tower being provided with a plurality of alternating baffles arranged in sets designated 24 and 25 so that any liquid vapor 45 passing through the tower will have a tendency to condense and pass back into the casing 22 and reservoir 3. The condensing tower also provides an outlet for the air drawn in through the opening 21 50 by the impeller so that a free current of air passes through the impeller to cool the water passing therethrough.

The construction of the impeller is such that it not only serves as means for effect-

ing the cooling of the liquid but also serves 55 as a fly wheel; therefore, I am enabled to construct a fly wheel of impeller form so that one element serves a dual purpose.

The construction of the blades 19 is such that the combined air and water will be directed with considerable force through the perimeter or rim of the fly wheel, thereby insuring efficient forced circulation of air of sufficient volume to absorb the greater portion of the induced heat in the cooling 65 water passing from the jacket.

In actual practice some of the water will be lost by evaporation and I, therefore, prefer to connect the normally closed inlet 26 of the reservoir 3 to a suitable supply pipe 70 27 so that the reservoir may be augmented from time to time. The inlet 26, however, is normally closed by a valve 28 provided with a float 29 capable of opening the valve 28 only when the level of the liquid within 75 the reservoir 3 drops below a certain point in the reservoir, the float being effective to close the valve as soon as the desired liquid level in the reservoir has been reached.

The particular construction of the impeller and fly wheel illustrated in the accompanying drawings need not be followed in all instances as the impeller is capable of various modifications without departing from the generic principles involved and, therefore, do not wish to be limited to the exact details shown but reserve the right to make such changes and alterations as properly come within the scope of the appended claim.

90 What I claim and desire to secure by Letters-Patent is:

In combination with an engine comprising a water jacket and a crank shaft, a hollow fly wheel on the crank shaft, having a slotted rim and a lateral air intake port, a hub on said wheel having an annular chamber provided with peripheral ports and with an annular side opening, a reservoir below the fly wheel, a casing enclosing the fly wheel and opening to the reservoir, means for delivering cooling liquid from the reservoir to the water jacket, and a conduit leading from the water jacket and delivering to the hub chamber through said annular opening.

95 In testimony whereof I affix my signature.
ARTHUR W. CAPS.
